SELF-LIFTING SADIRON

Allen F. Kipper, Glendale, and Louis B. Tucker-
man, Los Angeles, Calif., assignors to Conti-
nental Fire-Proof Iron Corp., a corporation of
Arizona

Application July 5, 1935, Serial No. 29,948

17 Claims. (Cl. 38—79)

Our invention relates to and has for a principal object the provision of a sad iron, preferably but not necessarily of the electrically heated type, and provided with means associated with the handle of the iron for automatically lifting the base of the iron substantially above a supporting surface when pressure on the handle is released and for supporting the iron in raised position when not in use.

A more detailed object is to provide a simple, effective and durable structure whereby the lifting device may be supplied as a part of an iron without materially increasing the cost over the usual type of sad irons, and for reducing the number of parts to a minimum. Other objects may appear as the description progresses.

An important feature of our invention consists in so mounting and forming the lifting means with angularly disposed arms with interconnecting rounded heel portions whereby when the iron is raised or lowered the lifting means will be caused to roll on the supporting surface for the iron and effect a corresponding longitudinal movement of the iron.

We have shown a preferred form of device in the accompanying drawing, in which:

Fig. 1 is a side elevation of a sad iron embodying our improvements with the lifting device operative for supporting the iron in raised position;

Fig. 2 is a similar view of the same with the lifting device arranged for supporting the base of the iron on a suitable surface;

Fig. 3 is a sectional plan of the same on line 3—3 of Fig. 2;

Fig. 4 is a rear end elevation of the sad iron;

Fig. 5 is a transverse section of the iron handle on line 5—5 of Fig. 1;

Figs. 6 and 7 are transverse sections on lines 6—6 and 7—7, respectively, of Fig. 2.

Our improved sad iron includes a conventional base 1 and a handle 2 spaced from said base and supported at opposite ends by means of straps 3 and 4. Said straps have vertically formed portions 5 and 6, respectively, which are attached to the ends of the handle 2 by means of screws as at 7, 7, and their lower extremities are suitably attached to the top of the base 1 by means of screws 8, 8.

The lifting device includes an auxiliary handle 9 of channelled cross section adapted to overlie the handle 2, an upper toggle member 10 and a pair of lower toggle members 11, 11, which are pivotally connected at 12 and a spring held rod 13 slidably supported in the handle 2 and pivoted

at 12 to the toggles 10 and 11, as shown in Figs. 1 and 2.

Handle 9 is pivotally supported on handle 2 at the front end of the iron at 14 preferably by means of an internal channel bar 15 which is welded at points 16 to the web of the handle 9 and ears 5' formed on and inwardly turned from the portion 5 of the handle strap 3. The channel bar 15 extends lengthwise of the handle 9 and is pivotally connected at 17 with the upper toggle member 10 so that when the handle 9 is in normal position, as shown in Fig. 1, the pivoted ends of the toggle members 10 and 11 will be adjacent the rear end of handle 2.

Rod 13 is slidable in a bore 18 of handle 2 and has a compression spring 19 held thereon between a nut 20 and the portion 6 of strap 4 whereby the toggle spring 19 is urged into the position shown in Fig. 1. Toggle members 11 are pivotally held at 21, 21, on opposite sides of the iron base 1 and have arms 21', 21' and feet 22, 22, extended downwardly at corresponding angles from their fulcrums 21, 21, which, when the handle 2 is released, are swung downwardly into horizontal planes parallel with the base 1 of the iron by the tension of spring 19 and serve to raise the iron into the position shown in Fig. 2 from a supporting surface 23. Intermediate feet 22 and arms 21' are rounded heel portions 22' on which the iron rocks when the same is raised and lowered, in a rolling movement, so as to reduce resistance and facilitate the operation of the lifting means.

Portion 6 of strap 4 has an elongated slot 24 therein through which rod 13 is extended and the outer end of said rod is flattened at 25 and has an elongated slot 26 therein for receiving the hinge pin 12, so that when the toggle device is operated the rod 13 will not bind on the strap 4 or the pin 12. Preferably the toggle 10 is of channelled cross section and is adapted to nest in the channel of member 15 when the handle 9 is depressed, as shown in Fig. 2, and the upper side of handle 2 is provided with a channel 27 which is adapted to receive the member 15 in such event.

In operation, it is obvious that when the handle is released the tension of spring 19 will draw the toggle joint 12 inwardly to a point adjacent the rear end of the handle and simultaneously depress the feet 22 of the toggle members 11, 11, so that the base 1 of the iron will be automatically raised above the supporting surface 23, thereby preventing the burning of the cloth on said surface and eliminating the necessity for placing the iron on a plate, as in ordinary cases.

When the iron is grasped in the hands of a user and pressure is applied to handle 9 said handle is moved downwardly until it embraces the handle 2 of the iron, thereby elevating the feet 22 and 5 lowering the iron base 1 upon the supporting surface 23.

The toggle arrangement shown and described provides a minimum range of movement for handle 9 in raising and lowering the iron and 10 substantially simplifies the operation and use of the iron as compared with other devices for the same purpose. The fulcrum points 22 are so positioned that the iron when raised above the supporting surface 23 will remain in a horizontal 15 position. In order to prevent the iron from remaining in an upright position in the event it may be dropped on the floor we provide a plate 30 attached at an end to the rear end of base 1 by means of a screw or screws 31 and having 20 an outwardly projecting portion 32 so formed that regardless of in what position the iron might light upon the floor it will be restored to the horizontal position shown in Fig. 1 and thereby prevent a fire as a result of the contact of the 25 rear end of the base with the floor. As the iron is raised the heels 22' of the lifting means roll on the surface on which the iron rests while the iron moves backwardly until it finally rests upon the surface 23 and the lifts are further elevated to 30 the position shown in Figure 2. When the iron is lowered the heels 22' first engage the surface 23 and roll thereon until the feet 22 assume the position shown in Figure 1, the iron moving forwardly until it assumes a position of rest.

35 Thus, an iron such as we have disclosed herein is fire-proof and safe, labor saving and durable. What we claim as new and desire to secure by Letters Patent is:

1. A self-lifting sad iron comprising: a base 40 adapted to rest upon a supporting surface, a handle, an operating member pivotally held on said handle, and lifting means including toggle members slidably and pivotally connected at a joint thereof to said handle, one of said toggle 45 members being connected with said operating member, another of said toggle members being hinged to said base and having means engaging said supporting surface for supporting said base out of contact with said surface when said handle 50 is released.

2. A self-lifting sad iron comprising: a base 55 adapted to engage a supporting surface, a handle on said base, an auxiliary handle pivotally attached to said handle and forming an operating member, and a lifting device including a link pivotally secured to said operating member and a pair of levers having upwardly extended arms and depending feet hinged at intermediate points to opposite sides of said base and pivotally connected through said arms with said link, the feet 60 of said levers being adapted to engage said supporting surface, and means on said handle for tensioning said link and said levers for raising said base out of contact with said supporting surface when said handle is released.

3. A self-lifting sad iron comprising: a base 70 adapted to engage a supporting surface, a handle on said base, an auxiliary handle pivotally attached to said handle and forming an operating member, and a lifting device including a link pivotally secured to said operating member and a pair of levers having upwardly extended arms and depending feet hinged at intermediate points to opposite sides of said base and pivotally connected through said arms with said link, the

feet of said levers being adapted to engage said supporting surface, and means on said handle for tensioning said link and said levers for raising said base out of contact with said supporting surface when said handle is released, said auxiliary handle being of arcuate cross section and adapted to overlie said handle when said feet are inoperative. 5

4. A self-lifting sad iron comprising: a base adapted to engage a supporting surface, a handle on said base, an auxiliary handle pivotally attached to said handle and forming an operating member, and a lifting device including a link pivotally secured to said operating member and a pair of levers having upwardly extended arms 15 and depending feet hinged at intermediate points to opposite sides of said base and pivotally connected through said arms with said link, the feet of said levers being adapted to engage said supporting surface, means on said handle for 20 tensioning said link and said levers for raising said base out of contact with said supporting surface when said handle is released, and means attached to an end of said sad iron and cooperating with said feet for preventing contact of said base 25 with said supporting surface when said auxiliary handle is released.

5. A self-lifting sad iron comprising: a base adapted to engage a supporting surface, a handle on said base, an auxiliary handle pivotally attached to said handle and forming an operating member, and a lifting device including a link pivotally secured to said operating member and a pair of levers having upwardly extended arms and depending feet hinged at intermediate points 30 to opposite sides of said base and pivotally connected through said arms with said link, the feet of said levers being adapted to engage said supporting surface, and means on said handle for tensioning said link and said levers for raising 35 said base out of contact with said supporting surface when said handle is released, said feet being disposed substantially parallel to the bottom of said base when said base is in raised position.

6. A self-lifting sad iron comprising: a base 45 adapted to rest upon a supporting surface during an ironing operation, a handle spaced from said base, an operating member of arcuate cross section hinged to an end of said handle and adapted to overlie the handle when in depressed position, 50 a tensioning means mounted within said handle, and a toggle having one member pivoted intermediate its ends to said base, the joint of said toggle being connected with said tensioning means, and the other member connected with said operating member, said first mentioned toggle member including a foot on each side of said base for raising said base out of contact with its supporting surface when said operating member and said handle are released and operable for lowering 60 said base into contact with said surface when said operating member is depressed. 55

7. A self-lifting sad iron comprising: a base adapted to rest upon a supporting surface during an ironing operation, a handle spaced from 65 said base, an operating member of arcuate cross section hinged to an end of said handle and adapted to overlie the handle when in depressed position, a tensioning means mounted within said handle, and toggle means having one member 70 thereof formed at its lower ends with a pair of feet positioned respectively at opposite sides of said base, said toggle means being connected to said tensioning means, whereby said toggle means is operated to depress said feet against said sup- 75

porting surface for raising said base out of contact with its supporting surface when said operating member and said handle are released and operable for lowering said base into contact with said surface when said operating member is depressed, said first mentioned member of said toggle means being hinged intermediate its ends to said base at the end of said sad iron opposite from the fulcrum of said operating member.

10 8. A self-lifting sad iron comprising: a base adapted to rest upon a supporting surface during an ironing operation, a handle spaced from said base, an operating member of arcuate cross section hinged to an end of said handle and adapted 15 to overlie the handle when in depressed position, a tensioning means mounted within said handle, and toggle means formed at its lower ends with a pair of feet positioned respectively at opposite sides of said base, said toggle means being 20 connected to said tensioning means, whereby said toggle means is operated to depress said feet against said supporting surface for raising said base out of contact with its supporting surface when said operating member and said handle are 25 released and operable for lowering said base into contact with said surface when said operating member is depressed, said toggle means including extensions from said feet, said extensions being pivoted intermediate their ends to said base and a 30 single link commonly connected with said extensions and also pivoted to said operating member, said tensioning means including a spring tensioned between said handle and the joint between said link and said extensions.

35 9. A self-lifting sad iron comprising: a base adapted to rest upon a supporting surface during an ironing operation, a handle spaced from said base, an operating member of arcuate cross section hinged to an end of said handle and 40 adapted to overlie the handle when in depressed position, a tensioning means mounted within said handle, and toggle means formed at its lower ends with a pair of feet positioned respectively at opposite sides of said base, said toggle means being 45 connected to said tensioning means, whereby said toggle means is operated to depress said feet against said supporting surface for raising said base out of contact with its supporting surface when said operating member and said handle 50 are released and operable for lowering said base into contact with said surface when said operating member is depressed, said toggle means including extensions from said feet, said extensions being pivoted intermediate their ends to said base and a single link commonly connected with said extensions and also pivoted to said operating member, said tensioning means including a spring tensioned between said handle and the joint between said link and said extensions, 55 said handle being channelled to provide a seat for said link when said operating member is depressed.

60 10. A self-lifting sad iron comprising: a base, a pair of laterally spaced feet pivotally attached to an end thereof and having upwardly projecting extensions, a link pivotally secured to the upper extremities of said extensions, a handle secured to said base, an operating member pivotally attached to an end of said handle and hinged to said link, and tensioning means carried by said handle and connected with said extensions for automatically swinging said extensions and depressing said feet against a surface for elevating said base above said surface when said operating member is released.

65 11. A self-lifting sad iron comprising: a base, a pair of laterally spaced feet pivotally attached to an end thereof and having upwardly projecting extensions, a link pivotally secured to the upper extremities of said extensions, a handle secured to said base, an operating member pivotally attached to an end of said handle and hinged to said link, and tensioning means carried by said handle and connected with said extensions for automatically swinging said extensions and depressing said feet against a surface for elevating said base above said surface when said operating member is released, said feet being disposed longitudinally of said base when said operating member is free and elevated above the bottom of said base when the operating member is depressed.

70 12. A self-lifting sad iron comprising: a base, a handle attached thereto, an operating member hinged to said handle and formed to overlie the handle when in depressed position, a link pivotally secured to and at a point intermediate the ends of said operating member, a pair of levers having upwardly extending arms and depending feet hinged at intermediate points to opposite 75 sides of said base, said arms being hinged to said link, and tensioning means carried by said handle and operatively connected with said link and said arms for automatically swinging said levers for disposing said feet in position for supporting 80 said base out of contact with a supporting surface when said operating member is released and tensionable when said member is depressed to lower said base into contact with its supporting surface.

85 13. A self-lifting sad iron comprising: a base, a handle attached thereto, an operating member hinged to said handle and formed to overlie the handle when in depressed position, a link pivotally secured to and at a point intermediate the 90 ends of said operating member, a pair of levers having upwardly extending arms and depending feet hinged at intermediate points to opposite sides of said base, said arms being hinged to said link, and tensioning means carried by said handle and operatively connected with said link and said arms for automatically swinging said levers for disposing said feet in position for supporting said base out of contact with a supporting surface when said operating member is released and tensionable when said member is depressed to lower said base into contact with its supporting surface, said handle having a channel 95 therein for receiving said link when said operating member is depressed.

100 14. A sad iron including an operating member movably mounted thereon, a base, an operating member carried by said base, toggle means formed with feet, said toggle means being pivotally connected to said base and operatively connected to said operating member, and means for automatically swinging said toggle means, when said operating member is released, for depressing said feet against a supporting surface for supporting said base out of contact with said surface.

105 15. A sad iron including an operating member movably mounted thereon, a base, an operating member carried by said base, toggle means formed with feet, said toggle means being pivotally connected to said base and operatively connected to said operating member, and tensioning means for automatically swinging said toggle means, when said operating member is released, for depressing said feet against a supporting surface.
